UNITED STATES PATENT OFFICE.

BENJAMIN HARRY JONES, OF ALLEGANY, NEW YORK.

CLOTHES BASKET.

Application filed July 21, 1924. Serial No. 727,372.

This invention appertains to receptacles and more particularly to baskets utilized for handling clothes incident to the hanging up thereof to dry on a clothes line or the like.

5 The primary object of this invention is to provide an improved clothes basket embodying a main compartment for the reception of the clothes, and end compartments for the reception of the clothes pins, thereby preventing loss of the clothes pins and the trouble relative to the handling of the pins during the hanging up of clothes on the line.

10 A further object of the invention is the provision of novel means for arranging the partitions, forming the compartments, in the body of the basket, whereby the pins can be easily removed from their compartment.

15 A further object of the invention is to provide novel means for weaving the partitions in the body of the basket, whereby the displacement of the partitions is eliminated.

20 A still further object of the invention is to provide an improved clothes basket of the above character, which will be durable and efficient in use, one that will be simple and easy to manufacture and one which can be placed upon the market at a small cost.

25 With these and other objects in view, the invention consists in the novel construction, arrangement, and formation of parts, as will be hereinafter more specifically described, claimed, and illustrated in the accompanying drawings, in which drawings,

30 Figure 1 is a top plan view of the improved basket,

Figure 2 is a side elevation of the same,

35 Figure 3 is a longitudinal section through the basket taken on the line 3—3 of Figure 1 showing the partitions in the basket,

40 Figure 4 is a fragmentary horizontal section taken through the basket on the line 4—4 of Figure 2 looking in the direction 45 of the arrows and illustrating the means of connecting the lower end of one partition in the basket.

45 Figure 5 is a fragmentary longitudinal sectional view through the basket showing 50 the slightly modified form thereof,

Figure 6 is a fragmentary horizontal section taken on the line 6—6 of Figure 6 looking in the direction of the arrows.

55 Referring to the drawings in detail, wherein similar reference characters des-

ignate corresponding parts throughout the several views the letter A generally indicates the improved basket, which comprises the body B divided by novel partitions C into a main clothes receiving compartment 60 D and clothes pin receiving compartments E and F.

The body of the basket B is constructed in the same manner as ordinary clothes baskets and embodies longitudinally extending splints 10 and transversely extending splints 11. These splints are interwoven together in the usual manner and have their ends bent up as at 12 and 13 respectively to form a part of the end and side walls 65 of the basket.

Suitable body splints 14 are interwoven with the bent portions 12 at 13 as clearly shown in the drawing to complete the end 70 and side walls. As shown some of the splints 14 are formed relatively wide and others relatively narrow and these relatively broad and relatively narrow splints are so arranged as to enhance the appearance of the basket. The upper edge of the basket is 75 reinforced by marginal bands 15 which are held in place by binding strips 16. The end walls of the basket can be provided with suitable handles 17.

80 The novel partitions C embody upright splints 18 and 19 and these splints are woven together by transverse splints 20. As clearly shown in Figures 1 and 3 the splints 19 are passed over the adjacent transverse splint 11 of the body of the basket and under the next transverse splint as indicated by the reference character 21. The splints 18 are 85 passed under the adjacent transverse splint 11 and are then bent back as at 22 under the transverse splints 20 of the partitions. The upper terminals of the partitions are reinforced by transverse strips or cleats 23 held 90 in place by relatively narrow binding strips 24 which are woven over the reinforcing strips 15 and binding strips 16 of the body 95 of the basket. It is obvious, by the foregoing, that the partitions will be held firmly 100 in place. It is also to be noted that the partitions C gradually incline toward the end walls of the basket, so as to permit the convenient grasping of the clothes pins.

105 In Figures 5 and 6 I have shown novel means for connecting the ends of the partitions C in place throughout the entire height thereof and as shown the transverse strips 110

20 thereof are passed under the adjacent extensions 13 of the transverse body splints 11, as at 25. In all other respects the basket shown in Figures 5 and 6 is the same as the basket shown in Figures 1 to 4.

From the foregoing description, it can be seen that I have provided a novel clothes basket which is formed with a main clothes receiving compartment and end clothes pin 10 receiving compartments.

Changes as to detail may be made without departing from the spirit or the scope of this invention, but—

What I claim as new is—

15 1. In a clothes basket, the combination with a body including side and end walls and a bottom wall formed of transverse and longitudinally extending interwoven splints, of a partition arranged in the body including upright splints and transversely extending splints woven together, the lower terminals of certain of the upright splints of the partition being passed forwardly under and then rearwardly over the adjacent transverse 20 splint of the bottom wall of the body and secured under the lower transverse splint of the partition.

2. In a clothes basket, the combination with a body including side and end walls and a bottom wall formed of transverse and longitudinally extending interwoven splints, of a partition arranged in the body including upright splints and transversely extending splints woven together, the lower terminals 25 of certain of the upright splints of the partition being passed forwardly under and then rearwardly over the adjacent transverse splint of the bottom wall of the body and secured under the lower transverse splint of the partition, and extensions formed on 30 the transverse splints of the partition and

secured between the splints of the side walls of the body of the basket.

3. In a clothes basket, the combination with a body including side and end walls 45 and a bottom wall formed of transverse and longitudinally extending interwoven splints, of a partition arranged in the body including upright splints and transversely extending splints woven together, the lower terminals 50 of certain of the upright splints of the partition being passed forwardly under and then rearwardly over the adjacent transverse splint of the bottom wall of the body and secured under the lower transverse 55 splint of the partition and the lower terminals of the other upright splints of the partition being passed over the adjacent transverse splint of the bottom wall of the body and secured between the next transverse 60 splint and the longitudinally extending splints of the body.

4. In a clothes basket, the combination with a body including side and end walls and a bottom wall formed of transverse and longitudinally extending interwoven splints, of a partition arranged in the body including upright splints and transversely extending 65 splints woven together, the lower terminals of certain of the upright splints of the partition being passed forwardly under and then rearwardly over the adjacent transverse splints of the bottom wall of the body and secured under the lower transverse splint of the partition, transverse cleats engaging the 70 upper terminals of the upright splints of the partition, and relatively narrow binding strips woven over the reinforcing cleats for binding the same to the body.

In testimony whereof I affix my signature.

BENJAMIN HARRY JONES.
